Application June 20, 1940, Serial No. 341,487
 In Poland April 26, 1935

9 Claims. (Cl. 250—40)

1

The present application is a continuation in part of my application Serial No. 73,865, filed April 11, 1936, Patent No. 2,216,829, issued October 8, 1940.

The present invention relates to electronic reactance circuits comprising an electron discharge tube arranged to act as an effective reactance; that is, either as a capacity or inductance, the value of which is controlled purely electrically by adjusting the amplification or internal impedance of the tube such as by controlling the bias potential applied to a grid or other control electrode.

More particularly the invention is concerned with variable reactance tube circuits of the type wherein amplified output potential is fed back from the output circuit to the input circuit of the tube in quadrature phase relation to the current in the input circuit to produce a "wattless" reaction being the equivalent of a variation of the apparent reactance of the circuit.

Variable reactance tubes of the above type have various uses in practice, particularly for controlling the resonant frequency of a tuned circuit purely electrically without mechanically moving parts such as in automatic tuning systems for radio receivers or for phase and frequency modulation purposes and other applications.

An object of the invention is to provide an electronic reactance circuit which is both simple in design and efficient in operation compared with circuits known in the prior art.

Another object is to provide an electronic reactance circuit which may be easily associated with a discharge tube already present in a circuit for other purposes such as the oscillator tube in a superheterodyne receiver.

These and further objects and advantages of the invention will become more apparent from the following detailed description taken with reference to the accompanying drawing forming part of this specification and wherein;

Figure 1 is a circuit diagram for a tuned amplifying stage embodying a "wattless" reaction or feedback circuit according to the invention for controlling the tuning or frequency response of the stage.

Figure 2 is a vector diagram explanatory of the function of the circuit according to Figure 1.

Figure 3 is a modification of the circuit arrangement according to Figure 1.

Figure 4 is a circuit diagram showing the circuit according to the invention incorporated in a superheterodyne receiver to produce an automatic tuning or frequency control.

2

Like reference characters identify like parts in the different diagrams of the drawing.

Referring to Figure 1, item 10 represents a source of alternating current such as high frequency signals arranged to excite a resonant circuit comprised of an inductance coil 12 having in series therewith a resistance 14 and being shunted by a tuning condenser 13. Item 11 is a coupling coil for impressing the signal currents from the source 10 upon the resonant circuit. In the example shown the resonant circuit forms the input coupling for an electron discharge tube 15 of any known type comprising in the example shown a cathode 16, an input control grid 17, a positively biased screen grid 25 and an anode or plate 18. The capacitative signal potential developed across the condenser 13 is impressed upon the grid-cathode path of the tube 15 resulting in corresponding amplified current variations in the anode or output circuit of the tube. The latter includes a tuned circuit comprised of an inductance 20 shunted by a condenser 22. The inductance 20 is coupled with a further inductance 21 connected to a further amplifier or a utilization circuit by way of output terminals c—d. Item 19 is a known grid biasing network comprising a resistance by-passed by a condenser and connected between the cathode and ground 24 or any other zero potential point of the system.

Thus far the circuit described constitutes a tuned R. F. amplifier stage well known to those skilled in the art. In accordance with the present invention a portion of the amplified output energy is fed back in quadrature relation to the energy in the input or tuned circuit 12—13—14 by the provision of a regenerative or feedback path connected across the anode and cathode or ground and comprising a condenser 23 serving as a blocking condenser and the resistance 14 in series with the input circuit.

The function of "wattless" or reactive feedback obtained in a circuit above described will be explained in the following: Starting with the oscillatory or circulatory current I flowing in the resonant circuit 12—13—14 whose tuning adjustment is to be controlled, the capacitative potential developed across the condenser 13 and impressed upon the grid-cathode path of the tube 15 will lag the current I by an angle of 90° well understood by those familiar with the theory of alternating current circuits. As a result thereof the potential developed on the plate 18 will lead the current I by the same angle due to the phase reversal by the tube; that is, by 90°. Providing the condenser 23 has a sufficiently high capacity

and the resistance 14 has a sufficiently high value, it is seen that the feedback current through the circuit 23—14 will be in phase with the potential at the plate 18; that is, it will lead the current I in the circuit, this being the equivalent of an effective increase of the inductive voltage drop in the circuit and accordingly an apparent increase of the inductance of the tuned circuit. The amount of this apparent inductance increase is determined by the amplitude of the current fed back; that is, in turn by the amplification or internal impedance of the tube 15. The latter may be controlled in any known manner such as by means of an adjustable grid bias supplied by way of terminals a—b and controlled either manually or automatically as will be understood.

If the resistance 14 has a comparatively small value an exact reactive feedback is still obtainable by the proper size of the condenser 23 as will be understood by reference to Figure 2. In the latter the vector E_{12} represents the inductive voltage drop developed across the tuning inductance 12 and leading the current I by 90° . The voltage drop E_{14} developed across the resistance 14 is in phase with the current I, thus yielding a resultant vector $E_{12,14}$ equal to and of opposite phase to the potential drop E_{13} developed across the condenser 13 and impressed upon the grid-cathode path of the tube 15. The voltage between the plate 18 and cathode is in turn opposite to the potential E_{13} due to the phase reversal effected by the tube and has a magnitude determined by the amplification constants or transconductance of the tube. This holds true exactly if the output circuit 20—22 is in tune with the signal frequency and accordingly constitutes substantially an ohmic impedance so as not to introduce any additional phase shift of the output current. Since the sum of the potential drops developed by the condenser 23 and the resistance 14 forming the feedback path both being at quadrature must be equal to the anode voltage E_{18} it is seen that by proper design of the condenser 23 and the resistance 14 the respective potential drops E_{23} and E_{14} will be such that the latter constituting the effective regenerating or feedback potential impressed upon the input circuit leads the current I by exactly 90° , thereby producing the full effect of an apparent inductance increase of the circuit.

In Figure 3 there is shown a modified arrangement differing from Figure 1 in that the entire output current is passed through the feedback resistance 14, the latter being connected in series with the tuning condenser 13. A further blocking condenser 13' is provided to prevent short circuit of the anode to ground.

Figure 4 shows a circuit diagram for a superheterodyne receiver comprising an electron mixer tube of the pentagrid or similar type for changing the incoming signals of comparatively high frequency to intermediate signals of lower frequency in a manner well known and serving simultaneously as an electronic reactance for automatically tuning the receiver within a predetermined operating range to the frequency of an incoming signal.

Radio frequency signals which may be derived from a preceding radio frequency amplifier or directly from an antenna are impressed by way of input terminals a—b and coupling transformer primary 25 upon a tuned circuit comprising an inductance 26 in series with a blocking condenser 28 shunted by a tuning condenser 27. The tuned circuit 26—27—28 has its high potential side connected to the signal input grid 33 of an electron

mixer tube 29 while the low potential side of the circuit is connected to ground 24 or any other zero reference point of the system. The D. C. return of the grid 33 may be effected in any known manner such as through an AVC circuit indicated in the diagram. The mixer tube as shown is of the pentagrid type and comprises a cathode 30, a first oscillating control grid 31, a positive or anode grid 32, an input signal grid 33 shielded by a screen grid 34 and an anode or plate 35. Item 36 is a grid biasing network connected between the cathode and ground comprising a resistance bypassed by a condenser to provide proper biasing potential according to well known practice. Grids 31 and 32 are connected to a regenerative circuit system for producing local oscillations to be combined or mixed with the incoming signals so as to produce an intermediate frequency signal in the output circuit of the tube. The local oscillator comprises a tank circuit formed by an inductance 37 having in series therewith a resistance 39 and shunted by a tuning condenser 38. The high potential side of this tank circuit is connected to the oscillating control grid 31 through a coupling condenser 42 while the low potential side of the circuit is grounded. The positive or anode grid 32 is connected through a feedback coil 40 arranged in inductive relation with the oscillating inductance 37 to the positive pole of a suitable high potential source indicated by the plus sign and bypassed to ground by a condenser 41. The anode grid 32 is further connected to the junction between the oscillating inductance 37 and the resistance 39 through feedback condenser 43 in a manner similar to that described in connection with Figure 1.

The signals of intermediate frequency produced by combining the local oscillation with the incoming signals are transmitted by means of an output circuit tuned to the intermediate frequency comprising an inductance 45 shunted by a condenser 46 and connected between the plate 35 and a suitable high potential source indicated by the plus sign, the latter being bypassed to ground through a condenser 47. The intermediate frequency signals are applied by way of secondary winding 48 in inductive relation with the inductance 45 to an intermediate frequency amplifier indicated by the rectangle 49. A detector and audio amplifier 50 feeding a loud speaker or the like 51 is connected to the intermediate frequency amplifier in a manner well known. Item 52 represents a discriminator or frequency response circuit associated with the intermediate frequency which may be of any known type and serves to produce a potential varying in proportion to deviations of the intermediate signal frequency from the fixed intermediate frequency of the system. This frequency responsive (AFC) potential is impressed upon the oscillating control grid 31 through a series resistance 54 and by-pass condenser 53 to control the amount of oscillating current conveyed to the oscillating or anode grid 32 and in turn the quadrature or "wattless" feedback current impressed upon the tank circuit 37—38—39 through the feedback condenser 43; i. e., in turn the effective tuning adjustment of the circuit 37—38—39.

Thus, whenever the intermediate frequency deviates from the desired value due to a variation or drift of the signal frequency impressed by way of terminals a—b, a positive or negative frequency responsive potential is produced by the discriminator 52 resulting in a corresponding variation of the "wattless" feedback current and in turn of

the apparent reactance of the tank circuit both in sign and magnitude and within a predetermined range of frequency deviations. By proper adjustment of the polarity of discriminating potential, the detuning of the receiver will be automatically reduced to a minimum by the automatic frequency control of the local oscillator in the manner described. Contrary to the known automatic frequency control systems no special reactance or control tube is required when using a circuit as proposed by the present invention in addition to the other advantages and simplifications of both the design and operation of the system.

From the foregoing it will be evident that the invention is not limited to the specific circuits and arrangements of parts shown and disclosed therein for illustration, but that the principle of the invention will be susceptible of variations and modifications coming within the broader scope of the invention as defined in the appended claims. The specification and drawing are to be regarded accordingly in an illustrative rather than in a limiting sense.

I claim:

1. An electronic reactance circuit comprising an electron discharge tube having a cathode, an anode and at least one control electrode, a tuned circuit carrying high frequency current coupled to said cathode and control electrode, a non-reactive impedance serially inserted in said tuned circuit, an output circuit connected to said anode, and a feedback circuit path between said anode and cathode including said non-reactive impedance, and means for controlling the degree of amplification of said tube.

2. An electronic reactance circuit comprising an electron discharge tube having a cathode, an anode and at least one control electrode, a tuned input circuit carrying high frequency current comprising a capacitative and an inductive reactance in parallel, said tuned circuit being coupled to said control electrode and cathode, a non-reactive impedance in series with one of said reactances of said tuned circuit, an output circuit connected to said anode, and a feedback circuit path between said anode and cathode including said non-reactive impedance.

3. An electronic reactance circuit comprising an electron discharge tube having a cathode, an anode and at least one control grid, an input circuit carrying high frequency current comprising a condenser shunted by an inductance, said input circuit being coupled to said grid and cathode, an ohmic resistance in series with said inductance, an output circuit connected to said anode, and a feedback circuit path between said anode and cathode including said ohmic resistance.

4. An electronic reactance circuit comprising an electron discharge tube having a cathode, an anode and at least one control electrode, a tuned input circuit carrying high frequency current comprising an inductance and a condenser in parallel, said tuned circuit being coupled to said control electrode and cathode, an ohmic resistance serially inserted in said tuned circuit, a further tuned circuit, and an output circuit connected to said anode, said further tuned circuit and said resistance being serially inserted in said output circuit.

5. An electronic reactance circuit comprising an electron discharge tube having a cathode, an anode and at least one control grid, a tuned input circuit carrying high frequency current comprising an inductance shunted by a condenser, said input circuit being coupled to said grid and cathode, an ohmic resistance in series with said inductance, a substantially non-reactive output circuit coupled to said anode and cathode, and a capacitative circuit connection between said anode and the junction point between said inductance and said resistance.

10 6. An electronic reactance circuit comprising an electron discharge tube having a cathode, an anode and at least one control grid, a tuned input circuit carrying high frequency current comprising an inductance shunted by a condenser, said input circuit being coupled to said grid and cathode, an ohmic resistance in series with said inductance, a further tuned circuit coupled to said anode and cathode, and a capacitative circuit connection between said anode and the junction point between said inductance and resistance.

15 7. An electronic reactance circuit comprising an electron discharge tube having a cathode, an anode and at least one control grid, a tuned input circuit carrying high frequency currents comprising an inductance shunted by a condenser, said input circuit being coupled to said grid and cathode, an ohmic resistance serially inserted in said input circuit, a further tuned circuit, and an output circuit coupled to said anode and cathode, said further tuned circuit and said resistance being serially inserted in said output circuit.

20 30 8. An electronic reactance circuit comprising a space discharge tube provided with a cathode, an anode, and at least one control grid, a circuit traversed by alternating current including reactive and non-reactive impedance in series, means for impressing reactive voltage drop from said circuit upon said grid and cathode, and a feedback circuit path between said anode and cathode including said non-reactive impedance.

25 9. An electronic reactance circuit comprising a space discharge tube provided with a cathode, an anode, and at least one control grid, a circuit traversed by alternating current including reactive and non-reactive impedance in series, means for impressing reactive voltage drop from said circuit upon said grid and cathode, a feedback circuit path between said anode and cathode including said non-reactive impedance, and means for controlling the degree of amplification of said tube.
